UNITED STATES PATENT OFFICE.

JOHN T. LELAND, OF HERMAN, MINNESOTA.

COLLAPSIBLE TUBE.

Application filed August 18, 1922. Serial No. 582,777.

To all whom it may concern:

Be it known that I, JOHN T. LELAND, residing at Herman, county of Grant, and State of Minnesota, a citizen of the United States, have invented certain new and useful Improvements in Collapsible Tubes, of which the following is a specification, reference being had to the accompanying drawings, forming a part thereof.

10 My invention relates to collapsible tubes adapted for containing paint and like pasty or semi-liquid substances and to be caused to expel their contents by squeezing the tubes. My invention has for its object to 15 provide a double or compound tube of this general character adapted to hold, separately, two distinct compounds and to expel both at the same time so that they may readily be mixed together in definite proportions. A further object of my invention 20 is to provide a nozzle for such double or compound tubes having separate openings in it for the discharge of the separate compounds and a single cap adapted to close 25 both discharge openings.

With the objects above indicated, and other objects hereinafter explained, in view my invention consists in the construction and combination of elements hereinafter described and claimed.

Referring to the drawings, Figure 1 is a sectional view of a double collapsible tube embodying my invention.

Figure 2 is an end view of the same.

35 Figure 3 is a cross sectional view on line 3—3 of Figure 1.

Figure 4 is an end view of the cap, and

40 Figure 5 is a view showing the double collapsible tube in use for delivering separate compounds onto a brush.

In the drawings 2 indicates the outer or larger tube and 1 indicates the inner or smaller tube. These tubes are formed of the usual soft metal commonly used for paint tubes and the like. 3 indicates the shoulder of the outer or larger tube formed, as is usual in collapsible tubes, of somewhat thicker metal than that of which the body of the tube is formed having at its centre a 45 nozzle 4 of still thicker metal, sufficiently thick to receive screwthreads 5 for the screw cap 6.

55 The inner tube 1 is of smaller diameter than the outer tube, usually of about half that diameter so as to have about one-fourth the capacity of the outer tube, and has a

shoulder 7 and nozzle 8. The nozzle 8 has a central discharge opening through it and is relatively long so as to extend through a central opening through the nozzle 4 in 60 which it is secured by solder or other securing means.

At one side of the nozzle 4 a discharge opening 10 is formed in the shoulder 3 this discharge opening being relatively long in 65 proportion to its width so that the material forced through it will be discharged in the form of a ribbon.

The screw cap 6 is formed with a flange or arm 11 adapted to fit over and close the 70 discharge opening 10 when the cap is screwed into place.

The double collapsible tube thus described is particularly adapted and intended for containing and delivering as wanted for 75 use, the two compounds which together form the dentifrice described and claimed in an application for patent filed by me August 17, 1922, Serial No. 582,592 the inner tube 1 containing a compound including as one of 80 its ingredients, iodine, and the outer tube containing a compound including a sodium compound such as sodium chloride, and starch. When the cap 6 is removed pressure on the outer tube will cause its contents to be discharged through the opening 10 in the form of a ribbon onto a suitably placed tooth brush, as shown in Figure 5, and at the same time through the pressure transmitted to the inner tube through the contents of the outer tube, the inner tube will be caused to discharge its contents in a small stream onto 85 the flat ribbon discharged from the opening 10. The iodine of the stream discharged from the inner tube combines at once with the sodium compound of the ribbon discharged from the outer tube to form sodium iodide and at the same time will combine with the starch to form iodide of starch 90 which has a characteristic blue color.

100 It will of course be understood that I do not desire to be limited to the use of the double collapsible tube for dentifrices as it may obviously be used wherever it is found desirable to keep two substances separate but mix them together at the instant of use.

Having thus described my invention what I claim is:

110 1. A double collapsible tube comprising an outer tube having a central neck portion having an opening therethrough, and a discharge opening at one side thereof, and a

centrally disposed inner tube having a central nozzle adapted to extend through the opening in the neck of the outer tube.

2. A double collapsible tube comprising
5 an outer tube having a central neck portion having an opening therethrough, and a discharge opening at one side thereof, and a centrally disposed inner tube having a central nozzle adapted to extend through the
10 opening in the neck of the outer tube, and a cap for the neck portion of the outer tube adapted to close the discharge opening of both tubes.

3. A double collapsible tube comprising

an outer tube having a central neck portion 15 having an opening therethrough, and a discharge opening at one side thereof, and a centrally disposed inner tube having a central nozzle adapted to extend through the opening in the neck of the outer tube, and a 20 cap for closing the discharge opening of the inner tube and provided with a depending lip adapted to close the discharge opening of the outer tube.

In testimony whereof I hereunto affix my 25 signature.

JOHN T. LELAND.
